UNITED STATES PATENT OFFICE

ROBERT E. PENT, OF JENKINTOWN, PENNSYLVANIA

CONTAINER FOR CIGARS

Application filed October 16, 1931. Serial No. 569,151.

This application is a continuation in part of application Serial Number 509,393, filed January 17, 1931.

This invention relates to containers for 5 cigars and has as its object the production of a new and improved container of this type.

At the present time cigars are generally packed for sale in quantities which are multiples of five. The most usual type is the box 10 of fifty.

The Federal laws require that each of these boxes be sealed with a Government revenue stamp of the proper amount so positioned that it will be broken upon opening of the 15 box.

The Federal laws further require that 20 there appear upon the box the following three items (1) A caution notice (hereinafter more specifically set forth); (2) Classification indicia (hereinafter more specifically set forth); and (3) Zone indicia and quantity notice (hereinafter more specifically set forth).

The Federal laws further require that 25 when cigars in a box are retailed to a plurality of purchasers, each of whom buys some but not all of the cigars in the box, they must be kept in the box in which they were originally packed and must be offered 30 for sale directly from the container. (The usual practice in the sale of cigars is for the retail merchant to remove the box from the show-case and offer the box to a prospective 35 purchaser who selects his cigar. The merchant then replaces the box in the show-case.)

The above requirements of the Federal laws as to sale from the original container makes it very difficult for the retailer to display his cigar in containers more attractive

40 or having better humidifying qualities than the original box in which the cigars were received. If the merchant does use a container other than that in which the cigars were received he must place the original container along with its contents therein. Such 45 a course is objectionable because a larger container must be used, resulting in the loss of valuable show-case space; because extra material must be used in making the outside container; and because the merchandising con-

tainer as finally presented to the prospective buyer is not perfect in appearance and often fails to have its intended effect of pleasing the eye.

With the advent of cellophane as a general packing agent, individual cigars have been wrapped in cellophane containers, then packed into standard boxes which were labeled and sold in the manner hereinabove outlined. Several packers have also placed 55 cigars in multiples of five or ten in cellophane containers and packed these units into standard boxes which were labeled in the manner hereinabove outlined and then sold in accordance with the requirements of the 60 law as hereinabove outlined. These cellophane wrapped cigars were still subject to the condition requiring their sale from the original container and could not be transferred to another container for sale therefrom. 65

Government revenue stamps are based, among other things, on the number of cigars in a unit. These stamps are sold to cover units of three (3), five (5), ten (10), twenty 70 (20), twenty-five (25), fifty (50) and one hundred (100) cigars. When it is remembered that cigars are usually sold in standard boxes containing fifty (50) cigars it becomes obvious that it is impossible to wrap 75 cigars for sale in units of three (3) to a package (a number which an average purchaser often buys at one time) without making a package in which only forty-eight (48) instead of fifty (50) cigars are present, or 80 making a package in which there will be sixteen (16) units of three (3) cigars to a unit and two single cigars. 85

The first of these packages is not permissible and the second of these packages is objectionable. Federal regulations prohibit the sale of a box having less cigars than the number designated on the revenue stamp for that box. If the cigars are so packed that there will be two loose cigars, a loss to the merchant will occur on the loose cigars. 90

Similarly when cigars are packed in a standard box designated for twenty-five or one hundred, it is impossible to break them up into sales units in which there are three 100

(3) cigars to a unit without either the loss of at least one cigar to the box, which results in a box which does not meet the Federal regulations and therefore cannot be sold, or the inclusion of at least one odd cigar in the box.

From the above it is obvious that with present packing methods it is impossible to pack cigars in units of three (a most desirable sales unit) without creating an unlawful package or some ultimate loss.

Another very pertinent objection to the individual cigars whether presented for sale with or without cellophane or other equivalent transparent wrapping has been the fact that the butt end of the cigar was usually frayed as a result of wear in the purchaser's pocket. Attempts have been made to offer individual cigars in special containers which were intended to eliminate this deleterious result. These attempts have not met with signal success, however, because of the fact that the protective wrappings are comparatively expensive and because of the further fact that the resulting package is comparatively bulky. Frayed ends result not only in individual cigars carried in a pocket but also in cigars which are offered for sale in cellophane or equivalent packages in merchandising units of five.

It is the object of this invention to evolve a method of packing cigars and to produce a cigar unit in which all of the objections hereinabove set forth and present in the well known packing methods and packages used at the present time are avoided.

More particularly stated, one of the objects of this invention is to evolve a method of packing cigars wherein it will be possible to transfer the cigars from the original containers in which they were packed in the factory to a merchandising container in the retail store without in any way violating any of the Federal laws governing the vending of cigars.

Another object of this invention is to provide a method of packing cigars wherein it will be possible to vend cigars directly in smaller units than those which are on sale at the present time.

Another object of this invention is to provide a method of packing cigars wherein it will be possible to vend cigars directly in small desirable units of three (3) cigars to a unit.

Another object of this invention is to produce a merchandising packet of cigars which will in and of itself comply with all the Federal regulations governing the sale of cigars and which will in and of itself be a direct merchandising unit.

Another object of this invention is to produce a cigar packet which can be removed from the container in which it was originally packed at the factory and offered for sale

as a unit from some other container in the retail store.

Another object of this invention is to provide a cigar packet with protective reinforcing means which will have the dual function of protecting the cigars from fraying and serving to give the necessary notices required by the Federal laws governing the sale of cigars.

Another object of this invention is to provide a cigar packet consisting of one or more cigars placed in an envelope made of a flexible, transparent substance, such as cellophane, with means which will give the necessary notices required by the Federal laws governing the sale of tobacco products but which will be inconspicuous so as not to interfere with the viewing of the merchandise within the envelope and so as not to detract from the appearance of the packet.

Another object of this invention is to produce a reinforcing means for a cigar packet which will be comparatively cheap and easy to manufacture, simple to assemble and which will not result in a bulky packet.

These as well as other objects of this invention and advantages arising therefrom will become more evident from the following description and drawings which form a part thereof.

In the drawings Figure 1 is a perspective view of my improved packet designed to hold three cigars. The closed position of the packet is shown in full and dotted lines and the open position of the packet is shown by dot and dash lines.

Figure 2 is a section along the line 2-2 of Figure 1 taken immediately after the packet has been opened. The cigars and reinforcing strip have not been disturbed as yet. As far as the relative positions of the cigars and the indicia and reinforcing strip with respect to the envelope and envelope flap is concerned, the disclosure of this figure is exactly the same as that when the elements have been placed within the envelope during the packing operation and the extended flap is ready for turning and the envelope is ready for sealing. The only difference being that in the latter case no revenue stamp would appear on the packet. The cigars in the packet are not shown in section since it is felt that such a showing would tend to obscure the elements of invention being illustrated.

Figure 3 is a section along the line 3-3 of Figure 1 showing both the full and open position of the packet, the open position being shown by dot and dash lines. The cigars in the packet are not shown in section since it is felt that such a showing would tend to obscure the elements of invention being illustrated.

Figure 4 is a bottom view of the disclosure of Figure 1.

Figure 5 is a side view, looking from the

right, of the lower portion of the packet shown in Figure 1. The upper portion of the packet, including its contents, has been torn away for the purpose of clearness.

5 Figure 6 is a fragmentary side view, looking from the left, of the disclosure shown in Figure 1. The upper portion of the packet, including its contents, has been torn away for the purpose of clearness.

10 Figure 7 is a perspective view of a modified reinforcing and Federal indicia carrying member.

Figure 8 is a section on the line 8—8 of Figure 1.

15 Figure 9 is a perspective view showing a box packed with the novel packets herein disclosed. A portion of the front of the box has been broken away for the purpose of clearness.

20 Figure 10 is a perspective view of a modification wherein the indicia-and-reinforcing member is placed on the outside of the envelope so as to encompass the envelope member and its contents.

25 Figure 11 is a section taken along the line 11—11 of Figure 10.

Figure 11—A is a fragmentary section taken along the line 11—A of Figure 11.

30 Figure 12 is a perspective view of a modification showing a modified indicia-and-reinforcing member within the envelope. The cigars have been omitted for the purpose of clearness.

35 Figure 13 is a section along the line 13—13 of Figure 12.

Figure 14 is a perspective view of another modification showing another type of modified indicia and reinforcing strip within the envelope. The cigars have been omitted for the purpose of clearness.

40 Figure 15 is a section along the lines 15—15 of Figure 14.

Figure 16 is a perspective view of still another modification showing another type of indicia-and-reinforcing strip within the envelope.

45 Figure 17 is a section taken along the line 17—17 of Figure 16.

50 Figure 18 is a perspective view of still another modified type of indicia-and-reinforcing strip.

Figure 19 is a section taken along the line 19—19 of Figure 18.

55 Referring more particularly to the drawings wherein similar reference numerals denote similar parts, reference numeral 1 indicates my improved package as a unit. The packet 1 is composed of an envelope member 24 preferably made of cellophane or some other transparent substance having the qualities of cellophane. The envelope 24 has a permanently sealed end 2, a temporarily sealed end 3 which terminates in a closing 60 and stamp contacting flap 4, a front face 5,

a rear face 6 and left and right side faces 7 and 8 respectively.

The envelope shown is adapted to hold three cigars 17 of a certain size designed to be sold for a certain price.

70 The butt end of the cigars is protected by a U shaped cardboard indicia-and-reinforcing member 9. The indicia-and-reinforcing member 9 is wider than the cigars it is designated to protect (see Figure 3) and is composed of a bottom element 10, a right side member 11 and a left side member 12.

The member 10 has printed or otherwise impressed on the outer face thereof the zone indicia and quantity notice 13 required by the Federal regulations. This particular notice must give the factory number, its district and the number of cigars in the packet. In the specific case herein illustrated this notice reads as follows:

80 Factory No. 23

3

1st Dist. of Pa.

85 It, as well as the other notices hereinafter set forth, has not been written out on the drawings for the reason that the print would appear too small and that to make views large enough to clearly show this indicia on the drawings would unnecessarily multiply the 90 number of sheets of drawing. This notice has therefore been designated on the drawings by the words "Zone indicia and quantity notice".

95 The member 11 has printed or otherwise impressed on the outside face thereof, indicia designated as the "Caution notice" 14. In the specific case herein illustrated this notice reads as follows:

100 Factory #23 1st Dist. State of Pa. Notice— 105

The manufacturer of the cigars herein contained has complied with all the requirements of the law. Every person is cautioned not to use either this package for cigars or the stamp thereon again, nor to 110 remove the contents of this package without destroying said stamp under the penalties provided by law for such cases.

115 The member 12 has printed or otherwise impressed on the outer face thereof indicia designated as the Classification notice 15. In the specific case herein illustrated this notice reads as follows:

120 A. The cigars herein contained were manufactured to retail at not more than five cents each and are so tax paid.

125 The flap 4 at the open end of the envelope 24 is sealed by a revenue stamp 16 of the proper denomination. A cigar band 18 bearing cigar brand and other trade-mark or trade-name indicia is placed around the envelope at its upper end if desired.

130 In Figure 7 is illustrated a modified indicia-and-reinforcing member 19 in which

the element 20 is exactly the same as the element 10 of the member 9 and in which the elements 21 and 22 differ from the elements 11 and 12 respectively of the member 9 only in 5 the fact that the members 21 and 22 terminate in a pointed member 23 which facilitates the insertion of the indicia and stiffening member into the envelope.

Although the assembly of the above 10 closed packet and the packing of the packets in a container is believed to be obvious from the above disclosure yet to avoid any possibility of misunderstanding, the following detailed description is here given.

15 The operator starts with an envelope 24 permanently sealed at its end 2 and open at its end 3. The envelope is properly dimensioned to receive a certain specific number of cigars which are to form a single unit. (In 20 this particular illustration three cigars constitute the unit. But it must be remembered that the number of cigars in a packet may be varied from one cigar to any number making a handy sales unit. The basic structure of 25 the packet, however, is the same no matter how many cigars the packet contains.) The operator places the number of cigars required (in this case three), into each envelope with rounded end 25 first so that the rounded end 30 of the cigars 17 will contact with the closed end 2 of the envelope 24. The operator then inserts the indicia-and-reinforcing member into the package making it take the position shown by the full lines in Figure 1 wherein 35 the element 10 serves to stiffen the lower end of the packet 1 and protects the butt end of the cigars 17 and the elements 11 and 12 serve to stiffen the sides 7 and 8 respectively of the packet 1 and to protect the sides of the 40 cigars. The ensemble of the envelope 24, the cigars 17, and the indicia-and-reinforcing member 9 as it appears at this point is clearly illustrated by Figure 2, with the remnant of the revenue stamp removed. It is to be noted 45 that at this point the end of the envelope 24 forms an extended flap 4. (This ensemble is also clearly shown in Figures 1 and 3, with the revenue stamp removed, by the full lines representing the cigars 17, the indicia-and-re- 50 forcing member 9 and the envelope 24, and by the dot and dash lines representing the flap 4 in its extended or open position.)

The operator then applies the revenue stamp 16 in the position shown in Figures 1 55 and 3, thus securing the flap in its closed position and sealing the envelope.

The operator now takes the necessary number of packets and packs them in the container to form the package as shown in Figure 9, 60 wherein all the packets but one appear as having been placed in the container. (This disclosure is exactly the same as that which would represent that point in the unpacking or vending of the packets where one packet 65 has been removed for sale.) The container

may be sealed by a wafer bearing trade-mark indicia or in any other manner desired. The container is delivered to the retail merchant who may, if he desires, transfer the contents to a special sales receptacle without in any way violating the Federal regulations governing the sale of cigars since each packet constitutes a legal sales unit.

It is to be noted that the individual sales packets make not only for flexibility in packing as to individual containers for a group of packets but also for flexibility in packing and shipping from the manufacturer to the retailer. Both of these results are obtained because of the fact that the limit on the number of cigars in a box formerly fixed by the revenue stamps appearing on the box has been eliminated.

With the exception of the fact that the indicia-and-reinforcing member is placed on the outside of the packet so as to encompass the same the disclosure of Figures 10 and 11 is exactly similar to that shown in Figures 1 to 6 inclusive and Figures 8 and 9. Referring more particularly to Figures 10 and 11, reference numeral 1A denotes the packet as a unit which is composed of an envelope 24A, preferably made of cellophane or some other transparent substance having the qualities of cellophane. The envelope 24A has a 95 permanently sealed end 2A, a temporarily sealed end 3A which terminates in the closing stamp contacting flap 4A. The envelope as shown is adapted to hold three cigars 17 to be sold for a certain price. One end of the envelope is encompassed and stiffened by a U shaped cardboard indicia-and-reinforcing member 9A. The member 9A is composed of a bottom element 10A, a right side member 11A and a left side member 12A. The zone indicia and quantity notice 13A, the caution notice 14A and the classification notice 15A are printed or otherwise impressed upon the members 10A, 11A and 12A respectively. The envelope is sealed with a revenue stamp 16A of the proper denomination. The envelope also has thereon a cigar band (not shown since the portion carrying the same has been broken away) bearing trade-mark or other trade-name indicia. The component elements of the packet 1A set forth in this paragraph are exactly similar to those which are shown in the packet 1 disclosed in Figures 1 to 6 and 8 and 9 and for that reason will not be more particularly described.

It is to be noted that the indicia-and-reinforcing strip is so formed and placed as to be inconspicuous and will not interfere with a viewing of the contents of the envelope if the envelope is made of cellophane or similar material. This is obvious from an examination of the packet shown in the many modifications herein described and from an examination of the packets as they appear in a display box as shown in Figure 9. The qual- 130

ity of inconspicuousness is entirely due to the structure and particular position of the indicia bearing member and is entirely independent of the material of which the indicia bearing member is made.

The disclosure of Figures 12 and 13 differs from that shown in Figure 1 only in the structure of the indicia-and-reinforcing member. Instead of a **U** shaped reinforcing strip 9 there is used a flat indicia-and-reinforcing strip 26 which extends over the entire face of the packet as shown. The indicia-and-reinforcing strip 26 has inscribed on the outer face thereof so as to be visible from the outside of the packet the zone indicia notice 13, the caution notice 14 and the classification notice 15. These are shown by dotted lines in Figure 12.

The disclosure of Figures 14 and 15 differs from that shown in Figure 1 only in the structure of the indicia and reinforcing member. Instead of the **U** shaped indicia-and-reinforcing member 9 shown in Figure 1 a **U** shaped indicia-and-reinforcing member 9b is used. The member 9b differs from the member 9 only in the fact that it is formed to encompass the cigars on a face and two sides as shown, instead of on an end and two sides as shown by the member 9. The zone indicia notice 13 appears upon the element 13b, the caution notice 14 appears upon the element 14b and the classification notice 15 appears upon the element 15b. The notices are shown in dotted lines. It is obvious that these notices may all be placed upon one of the elements 13b, 14b or 15b.

The disclosure of Figures 16 and 17 differs from that of Figure 1 only in the structure of the indicia and reinforcing member. Instead of the **U** shaped indicia-and-reinforcing member shown in Figure 1, an **L** shaped indicia-and-reinforcing member 27 is used. The **L** shaped member is composed of a main face portion 28 and an end portion 29. The portion 28 contacts with and reinforces a face of the packet while the end portion 29 contacts with and reinforces an end of the packet as shown. The zone indicia notice 13, the caution notice 14 appear upon the member 28, while the classification notice 15 appears upon the end portion 29 as shown by the dotted lines in Figure 16. It is obvious that all of these notices may appear upon the portion 28 or the portion 29 if space permits in the manner illustrated upon the strip 26 in Figure 12 or that any one of the notices may be shifted to appear upon either the portion 28 or the member 29.

The disclosure of Figures 18 and 19 differs from the disclosure of Figure 16 and 17 only in the fact that the portion 29a of the indicia-and-reinforcing strip 27A is so placed as to contact with and reinforce a side instead of an end of the packet. The portion 28a is exactly similar to the portion 28. The zone

indicia notice 13, the caution notice 14 and the classification notice 15 are shown by dotted lines upon the portions 28a and 29a.

The disclosure of Figures 1 to 19 is merely illustrative of some of the many forms which the indicia-carrying member may take. In addition, the said indicia-carrying member may be made to take other forms without departing from the spirit of my invention, the essential feature of which lies in providing a cigar packet consisting of one or more cigars packed in a soft, flexible envelope with an independent strip which has inscribed thereon the indicia required by Federal regulations for making the packet a direct merchandising unit and which is so positioned on the said packet that the said required indicia is visible from the outside of the packet.

To form a packet which can be vended as a direct merchandising unit it is not necessary that the indicia carrying strip be made of cardboard or other relatively stiff material. It may be made of very thin paper or its equivalent.

The quality of inconspicuousness is due entirely to the structure and particular position of the indicia-carrying member and is wholly independent of the material of which the indicia bearing member is made. Therefore to produce a packet wherein the indicia-carrying member is inconspicuous the indicia-carrying member need not be made of cardboard but may be made of relatively thin paper or its equivalent.

By the use of a comparatively stiff indicia-carrying member, such as a member made of cardboard, relatively stiff paper or its equivalent, a triple function is imparted to the strip—viz:

- (1) It adapts the packet for being vended as a unitary merchandising unit;
- (2) It provides the packet with an indicia member which is inconspicuous; and
- (3) It provides the packet with stiffening means.

It is to be understood that my invention is not limited to a structure such as a relatively stiff indicia-carrying member which meets all of the independent objects of my invention but that it may take a form wherein the indicia-carrying strip is made of relatively thin paper and wherein it meets only one or several of the independent objects of my invention.

Definitions:—(a) The words "indicia-carrying member" as used in the specification and claims are used to denote broadly the member 9 of the Government identifying indicia designated generally by reference numerals 13, 14 and 15 which appears thereon without any limitations as to the qualities of the material of which it is made—that is—it may be made of thin paper, or of cardboard, or of relatively stiff paper or the equivalent of any one of these materials.

(b) The words "indicia-and-reinforcing member" as used in the specification and claims are used to denote the indicia-carrying member 9 and the Government identifying indicia designated generally by reference numerals 13, 14 and 15 which appears thereon when the said member is made of cardboard, relatively stiff paper, or its equivalent and serves as a reinforcing as well as 10 an indicia-carrying member.

(c) The words "required statutory indicia" as used in the specification and claims are used to denote broadly the zone indicia and quantity notice, the caution notice and the 15 classification notice hereinabove more fully described and designated by the reference numerals 13, 14 and 15 respectively, or the equivalents of the said notices.

The above disclosure is to be understood as 20 being by the way of illustration and not by the way of limitation since many changes may be made in the construction of the device herein disclosed without departing from the spirit of my invention. For instance, instead of using cellophane or some equivalent transparent material for the envelope, any 25 soft flexible material having the qualities necessary to serve as a container for this purpose may be used. This substance may be fully 30 transparent as shown, or partially transparent so as to expose the indicia appearing on the indicia-and-reinforcing strip 9, or it may even be opaque, in which case the indicia-and-reinforcing member 9 must be 35 pasted around the outside of the envelope: Envelopes which are transparent only in part or which are opaque are not herein shown because they are well known in the envelope art and because in the light of this 40 disclosure any one skilled in the art could easily substitute such envelopes for the cellophane envelope in the novel combination disclosed in this invention: Or instead of having three cigars in the packet, as shown, the 45 number may be decreased to two or one, or increased to any number desired making a handy sales unit. Some units known today are units of one, five and ten. The applicant cites these merely as illustrative of units 50 which might be used but does not limit himself to such units. However, no matter how many or few cigars contained in the packet, its structure will be the same as shown in Figures 1 to 19 inclusive. The only change in 55 the envelope and the indicia-and-reinforcing strip which will be necessary is one of degree to adapt the said envelope and indicia-and-reinforcing strip for use in connection 60 with either a greater or lesser number of cigars, as may be desired, than the three shown: Or, instead of making the indicia-and reinforcing member of cardboard, it may be made of relatively stiff paper or of any 65 other substance having the necessary qualities of lightness, stiffness and ability to have

indicia impressed thereon: Or the side elements of the indicia and stiffener member may be made longer. These as well as other changes may be made in my disclosure without departing from the gist of my invention. 70

For the above reasons it is my desire that the claims which are hereunto appended for the purpose of defining my invention should be limited only by the prior art.

Having described my invention what I 75 claim as new and useful is:—

1. As an article of manufacture a merchandising packet of cigars fully meeting the statutory requirements consisting of an envelope member made of soft, flexible material, 80 a plural number of cigars carried in said envelope, and an indicia-and-reinforcing member associated with the said packet and positioned for stiffening the same, the said indicia-and-reinforcing member having the required statutory indicia inscribed on the outer 85 face thereof.

2. As an article of manufacture a merchandising packet of cigars not exceeding ten in number and fully meeting the statutory requirements, consisting of an envelope made of soft, transparent, flexible material, a plural number of cigars in the said envelope the said number being equal to the number specified on the revenue stamp to be used in association 90 with the said packet, an indicia-and-reinforcing member associated with the said packet and positioned for encompassing, stiffening and reinforcing an end of the said packet, the said indicia-and-reinforcing member having the required statutory indicia inscribed thereon; and a revenue stamp of the proper 95 denomination sealing the said packet.

3. As an article of manufacture a merchandising packet of three cigars fully meeting 105 the statutory requirements, consisting of an envelope made transparent, thin, flexible material, the said envelope being permanently sealed at one end and temporarily sealed by a revenue stamp of proper amount at its other 110 end, the said revenue stamp being positioned for being broken when the temporarily sealed end is opened for the purpose of removing the said cigars from the said envelope; and indicia-and-reinforcing member carried by the 115 said envelope, the said indicia-and-reinforcing member being formed and positioned so as to encompass, protect and stiffen the sides and an end of the said envelope, the said indicia-and-reinforcing member having the required statutory indicia inscribed on the outer 120 face thereof.

4. As an article of manufacture a merchandising packet of three cigars fully meeting the statutory requirements, consisting of an envelope made of transparent, thin, flexible material, the said envelope being permanently sealed at one end and temporarily sealed by a revenue stamp of proper amount at its other end, the said revenue stamp being positioned 125 130

for being broken when the temporarily sealed end is opened for the purpose of removing the said cigars from the said envelope; the said cigars being positioned within the said envelope so that their rounded ends are adjacent to the said permanently sealed end of the said envelope and that their butt ends are adjacent to the said temporarily sealed end of the said envelope; and a U shaped indicia-and-reinforcing member so positioned within the said envelope intermediate one of the said ends of the said cigars and that end of the packet contiguous thereto as to encompass and protect the said end of the said cigars and to stiffen the said end of the said packet, the said indicia-and-reinforcing member having the required statutory indicia printed on the outer face thereof whereby the said indicia is visible through the said transparent envelope.

5. As an article of manufacture a merchandising packet of three cigars fully meeting the statutory requirements, consisting of an envelope made of transparent, thin, flexible material, the said envelope being permanently sealed at one end and temporarily sealed by a revenue stamp of proper amount at its other end, the said revenue stamp being positioned for being broken when the temporarily sealed end is opened for the purpose of removing the said cigars from the said envelope; the said cigars being positioned within the said envelope so that their rounded ends are adjacent to the said permanently sealed end of the said envelope and that their butt ends are adjacent to the said temporarily sealed end of the said envelope; and a U shaped cardboard indicia-and-reinforcing member positioned within the said envelope intermediate the butt ends of the said cigars and the temporarily sealed ends of the said envelope with the U bottom member serving to reinforce and stiffen the bottom of the packet and to protect the butt ends of the said cigars and with each of the U side members serving to reinforce and stiffen one of the sides of the said envelope and to protect the side of the cigar contiguous thereto; the said U bottom member having the required statutory indicia and quantity notice inscribed on the outer face thereof, one of the said U side members having the required statutory caution notice inscribed thereon, and the other of the said U side members have the required statutory classification notice inscribed thereon, whereby the said required statutory notices are visible through the said transparent envelope.

6. As an article of manufacture a cigar merchandising packet fully meeting the statutory requirements, consisting of an envelope made of transparent, flexible material, a revenue stamp of the proper denomination positioned on the said envelope for sealing the said envelope, a cigar carried within the said envelope, and a U shaped indicia-and-reinforcing member encompassing one of the

ends of the said cigar and positioned intermediate the said end of the said cigar and that end of the said envelope contiguous to the said encompassed end, the said indicia-and-reinforcing member having the required statutory indicia inscribed on the outer face thereof whereby the said indicia is visible through the said transparent envelope.

7. As an article of manufacture a merchandising cigar packet fully meeting the statutory requirements, consisting of an envelope of soft, flexible material, a revenue stamp of the proper denomination carried by the said envelope and positioned for sealing the said envelope, a cigar carried within the said envelope, and an indicia-and-reinforcing member associated with the said envelope and positioned for stiffening the same, the said indicia-and-reinforcing member having the required statutory indicia inscribed thereon so as to be visible from the outside of said envelope.

8. As an article of manufacture a merchandising cigar packet fully meeting the statutory requirements, consisting of an envelope of soft, flexible material, a cigar carried within the said envelope, and an indicia-and-reinforcing member associated with the said envelope and positioned for stiffening the same, the said indicia-and-reinforcing member having the required statutory indicia inscribed thereon so as to be visible from the outside of the envelope.

9. As an article of manufacture a merchandising packet of cigars, consisting of an envelope made of soft, flexible material, a revenue stamp of the certain denomination positioned on the said envelope for sealing the said envelope, a plural number of cigars carried within the said envelope, the said number of cigars being equal to the number specified on the said revenue stamp used in association with the said envelope and a U shaped indicia-and-reinforcing member associated with the said envelope and encompassing one of the ends of the said envelope for stiffening and reinforcing the said end of the said envelope, the said indicia-and-reinforcing member having the required indicia, inscribed thereon so as to be visible from the outside of the envelope.

10. As an article of manufacture a merchandising packet of cigars consisting of an envelope made of soft, flexible material, a revenue stamp of the proper denomination positioned on the said envelope for sealing the said envelope, a plural number of cigars carried within the said envelope, the said number of cigars being equal to the number specified on the said revenue stamp used in association with the said envelope, an indicia-and-reinforcing member associated with the said envelope and positioned for stiffening and reinforcing the said envelope, the said indicia-and-reinforcing member

having the required statutory indicia inscribed thereon so as to be visible from the outside of the said envelope.

11. As an article of manufacture a merchandising packet of cigars fully meeting the statutory requirements consisting of an envelope made of transparent, flexible material, one or more cigars carried within the said envelope, a revenue stamp of a denomination equal to the number of cigars within the said envelope positioned on the said envelope for sealing the said envelope, and an independent indicia-carrying member positioned within the said envelope intermediate the inner surface of the said envelope and the said cigars, the said indicia-carrying member having the required statutory indicia inscribed thereon so as to be visible from the outside of the said envelope.

12. As an article of manufacture a merchandising packet of cigars fully meeting the statutory requirements consisting of an envelope made of transparent, flexible material, one or more cigars carried within the said envelope, a revenue stamp of a denomination equal to the number of cigars within the said envelope positioned on said envelope for sealing the said envelope, and an L shaped independent indicia-carrying member positioned within the said envelope intermediate the inner surface of the said envelope and the said cigars, the said indicia-carrying member having the required statutory indicia inscribed thereon so as to be visible from the outside of the said envelope.

13. As an article of manufacture a merchandising packet of cigars fully meeting the statutory requirements consisting of an envelope made of soft, flexible, transparent material, one or more cigars carried within the said envelope, a revenue stamp of a denomination equal to the number of cigars within the said envelope positioned on said envelope for sealing the said envelope, and an independent U shaped indicia-carrying member positioned within said envelope intermediate the inner surface of the said envelope and the said cigars along an end and two sides of the said envelope, the said indicia-carrying member having the required statutory indicia inscribed thereon so as to be visible from the outside of the said envelope.

14. As an article of manufacture a merchandising packet of cigars fully meeting the statutory requirements consisting of an envelope made of soft, flexible, transparent material and having sides which are narrower than its faces, one or more cigars carried within the said envelope, a revenue stamp of a denomination equal to the number of cigars within the said envelope positioned on the said envelope for sealing the said envelope, and an independent U shaped indicia-carrying member positioned within

the said envelope intermediate the inner surface of the said envelope and the said cigars so as to contact with an end and two narrow sides of the said envelope, the said indicia-carrying member having the required statutory indicia inscribed on the outer face thereof so as to be visible from the outside of the said envelope.

15. As an article of manufacture a merchandising packet of cigars consisting of an envelope made of soft, flexible material, a revenue stamp of a certain denomination positioned on the said envelope for sealing the said envelope, a plural number of cigars carried within the said envelope, the said number of cigars being equal to the number specified on the said revenue stamp used in association with the said envelope, and a U shaped indicia-and-reinforcing member associated with the said envelope and positioned for stiffening and reinforcing the said envelope, the said indicia-and-reinforcing member having the required statutory indicia inscribed thereon so as to be visible from the outside of the said envelope.

16. As an article of manufacture a merchandising packet of cigars consisting of an envelope made of soft, flexible material, a revenue stamp of a certain denomination positioned on the said envelope for sealing the said envelope, a plural number of cigars carried within the said envelope, the said number of cigars being equal to the number specified on the said revenue stamp used in association with the said envelope, and an L shaped indicia-and-reinforcing member associated with the said envelope and positioned for stiffening and reinforcing the said envelope, the said indicia-and-reinforcing member having the required statutory indicia inscribed thereon so as to be visible from the outside of the said envelope.

In testimony whereof I hereby affix my signature.
